Primary Examiner — Mitchell Siegel(74) *Attorney, Agent, or Firm* — Quickpatents, LLC; Kevin Prince(57) **CLAIM**

I claim the ornamental design for a golf putt training device, as shown and described.

DESCRIPTION

FIG. 1 is a perspective view of a golf putt training device, showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing a putter and putter attachment in FIG. 1 depict environmental matter and form no part of the claimed design.
